HAT CLEANING DEVICE

Harry Schlesinger, Des Moines, Iowa, assignor to
 Cleaners Appliance Company, Des Moines,
 Iowa, a corporation of Iowa

Application June 10, 1933, Serial No. 675,186
 10 Claims. (Cl. 223—26)

This application is a continuation in part of my co-pending application filed September 23, 1929, Serial Number 394,633.

The object of my present invention is to provide a cleaning device for hats of simple, durable and comparatively inexpensive construction.

A further object is to provide a hat cleaning device to facilitate all operations relative to cleaning a hat before it is dried in the machine illustrated in my copending application.

More particularly, it is my object to provide a table-like device having a hat cleaning chamber extending downwardly from the top of the table with a hat block mounted in the chamber in such a way that the under surface of a brim of a hat may be cleaned by allowing the crown thereof to extend into the chamber or the block may be raised out of the chamber for positioning the crown of the hat on the block so that the block supports the crown of the hat when cleaning it with a brush and cleaning fluid.

Another object is to provide a conveniently operable control means for raising and lowering the hat block, as desired.

With these and other objects in view my invention consists in the construction, arrangement and combination of the various parts of my device, whereby the objects contemplated are attained, as hereinafter more fully set forth, pointed out in my claims, and illustrated in the accompanying drawing, in which:

Figure 1 is a plan view of a hat cleaning device embodying my invention.

Figure 2 is a sectional view of the same on the line 2—2 of Figure 1.

Figure 3 is a plan view of a slightly modified form of cleaning device.

Figure 4 is a sectional view on the line 4—4 of Figure 3.

Figure 5 is a side elevation of part of the device, looking in the direction of the arrow 5 on Figure 4 and

Figure 6 is a front view of a locking device, looking in the direction of the arrow 6 on Figure 5.

On the accompanying drawing, I have used the reference numeral 10 to indicate generally a table top. The table top 10 is supported on legs 12 which are suitably braced by angle iron frames 14 and 16 vertically spaced with relation to each other.

A shelf 18 is supported on the frame 16. The frame and table top are shown broken off at the left hand side of Figures 1 and 2.

My cleaning device includes a cleaning cham-

ber 20 extending downwardly from a depressed portion 22 of the table top 10. A removable cover 24 is provided for the chamber 20 when not in use.

A bearing sleeve or hub 26 is secured to the bottom of the chamber 20 and projects upwardly into the chamber. A shaft 28 is slidably mounted in the hub 26 and its lower end is slidably mounted in a bearing 30 formed on a bracket 32. A cross bar 34 is provided for supporting the bracket 32 relative to the frame 16.

A hat block 36 is removably positioned on a reduced portion 38 at the upper end of the shaft 28. Sockets 40 are formed in the hat block 36 so that it may extend down over the hub 26 when the hat block is in its lowermost position.

The hat block 36 is capable of rotation on the reduced portion 38 of the shaft 28 and is also reversible top for bottom so that either the dome-shaped end or the flat end may be positioned upwardly. A drain spout 42 is provided at the lower portion of the cleaning chamber 20 and may extend to a suitable receptacle. For the purpose of raising the hat block 36 and holding it in such position, I provide a lever 54 pivoted to a set collar 56.

The set collar 56 is secured to the shaft 28. The lever 54 is provided with a handle 58 for the convenience of the operator when swinging the lever.

A pair of spaced links 60 are pivoted to the bracket 32 and to the lever 54. The lever 54 may be caused to assume the dotted line position shown in Figure 2 by swinging the handle 58 downwardly. When in the dotted line position, a stop pin 62 engages the links 60 after an over-center position has been reached whereby the hat block 36 will remain in a raised position without fastening means being provided therefor. The hat block, however, may be maintained in any intermediate position by means of a set screw 64.

In the modified form of construction shown in Figures 3, 4, 5 and 6, similar parts will be referred to by similar reference characters with the addition of the letter *a*. The difference between the modified form of construction and the type of device thus far described lies principally in the manner of manipulating and adjusting the height of the hat block 36a. The shaft 28a is of tubular construction and is slidably mounted over a rod 66 secured to the cross frame member 68 and extending upwardly

therefrom. This construction provides for efficiently guiding the shaft 28a without binding and yet in a condensed space allows considerable movement of the shaft. The reduced pin 5 38a may be pressed into the upper end of the tubular shaft 28a or otherwise secured therein.

A bumper spring 70 is mounted on the rod 66 for the lower end of the tubular shaft 28a to strike against when lowering the hat 10 block 36a.

A control handle 72 is provided on a bell crank shaped arm 74. The arm 74 is provided with a pair of clamping devices 76 which are clamped to the tubular shaft 28a for moving 15 the shaft whenever the handle 72 is moved.

A lock is provided for the arm 74 and consists of a bracket 78 having a stationary shoe 80 and a pivoted cam shoe 82. The arm 74 is adapted to be engaged by the shoes 80 and 20 82, a spring 84 being provided for swinging the cam 82 against the arm 74. The cam shoe 82 is so designed as to prevent any downward movement of the arm 74 and consequently the hat block 36a, when the cam is released and 25 the spring 84 is allowed to function, as shown in Figure 6. By swinging the handle portion 86 to the right, the arm 74 is released so that it can drop by gravity or the operator can adjust it to a lower position, as desired. To adjust 30 the hat block to a higher position, it is merely necessary to pull upwardly on the handle 72, which releases the cam 82, but locks it again as soon as any downward movement of the arm 74 is attempted or when the handle 72 is released.

In connection with the table top 10, I have 35 illustrated a small container 88 adapted to contain a cleaning fluid and covered by a lid 90. A drain pipe 92 may be provided for draining 40 the cleaning fluid from the container 88 into the cleaning chamber 20a from which the cleaning fluid may be drained through the pipe 42a. A drain cock 94 is provided to cut off 45 communication between the container 88 and the drain pipe 92.

Practical operation

In the operation of my device, the under surface of a brim of a hat may be cleaned by inverting the hat in the dotted line position indicated at 96 in Figure 2. A small brush is dipped into a cleaning fluid and the brim of the hat brushed. It will be noted that the crown of the hat projects into the cleaning chamber 20 without any interference from the hat block 36. After the under surface of the brim has been cleaned, the upper surface of the brim may be cleaned by placing the hat right side up on the table top. The crown of the hat may be cleaned 55 by raising the block 36 to its upper position to fit into the crown of the hat. In the case of straw hats 98, as shown in dotted lines in Figure 4, the flat side of the hat block may be arranged uppermost.

65 All cleaning fluid draining from the hat will flow into the cleaning chamber 20 and may be subsequently drained therefrom and filtered for re-use.

The hat after being cleaned in the present device 70 can be dried and deodorized in the machine illustrated in my co-pending application.

Some changes may be made in the construction and arrangement of the parts of my device without departing from the real spirit and purpose 75 of my invention, and it is my intention to

cover by my claims, any modified forms of structure or use of mechanical equivalents, which may be reasonably included with their scope.

I claim as my invention:

1. Hat cleaning mechanism, comprising a supporting surface having an opening therein through which the crown of an inverted hat may project downwardly, a hat block mounted below a hat when in such position, and means for 10 raising said hat block to a position above said surface whereby to be received in the crown of a hat, said means comprising a handle fixed relative to said block and a lock for said handle.

2. Hat cleaning mechanism, comprising a 15 supporting surface having an opening therein through which the crown of an inverted hat may project downwardly, a hat block mounted below a hat when in such position, means for raising said hat block to a position above said surface whereby to be received in the crown of a hat, said means comprising an arm fixed relative to said block and a lock for said arm, said lock comprising a cam to engage said arm to hold it against the force of gravity.

3. Hat cleaning mechanism comprising a 20 cleaning chamber, a vertically slidable shaft projecting upwardly thereinto, a hat block on said shaft and means for raising said shaft to a position with said hat block above said chamber, said chamber having a hub extending upward from the bottom thereof for said shaft to extend thru, said hub being so connected with said bottom as to prevent leakage of liquid between the bottom and hub, a liquid outlet for 25 said chamber, said hub extending to a level thereabove to prevent leakage of liquid from said chamber around said shaft, said hat block having a socket to fit over said hub.

4. In a device of the class described, a pair of 30 spaced supports, a sleeve slidable through one of said supports, a rod on the other one and projecting into the sleeve, a hat block carried by and a handle secured to the sleeve and an eccentric lock for said handle, said lock being 35 spring actuated to lock the handle against downward movement.

5. In a device of the class described, a pair of 40 spaced supports, a sleeve slidable through one of said supports, a rod on the other one and projecting into the sleeve, a hat block carried by and a handle secured to the sleeve and an eccentric lock for said handle, said lock being 45 spring actuated to lock the handle against downward movement but being arranged to allow 55 upward movement without the necessity of manually shifting the eccentric lock.

6. Hat cleaning mechanism comprising a 60 cleaning chamber, a vertically slidable shaft projecting upwardly thereinto, a hat block on said shaft and means for raising said shaft to a position with said hat block above said chamber, said means comprising a handle and a locking cam therefor whereby manipulation of the cam will allow the hat block to move downwardly 65 by gravity and the handle may be moved upwardly without manipulating the cam.

7. In hat cleaning mechanism, a hat block, means for raising said hat block comprising an arm fixed relative to said block and a lock 70 for said arm, said lock comprising a cam to engage said arm to hold it against the force of gravity.

8. In a device of the class described, a frame, a pair of spaced supports thereon, a sleeve slid- 75

able through one of said supports, a rod on the other one and projecting into the sleeve, a hat block carried by the sleeve, a spring bumper on the rod for the sleeve to engage when in its lowest position, a handle secured rigidly to said sleeve and slideable along said frame in a path parallel to the axis of said sleeve and a lock on said frame for engaging said handle to lock it against movement and thereby retain the hat block in a desired position.

9. In a device of the class described, a pair of spaced supports a sleeve slideable through one of said supports, a rod on the other one and projecting into the sleeve, a hat block carried by and

a handle secured to said sleeve and an eccentric lock for said handle to lock it against downward movement.

10. In a device of the class described, a pair of spaced supports, a sleeve slideable through one of said supports, a rod on the other one and projecting into the sleeve, a hat block carried by and a handle secured to said sleeve and an eccentric lock for said handle to lock it against downward movement but being arranged to allow upward movement without the necessity of manually shifting the eccentric lock.
